UNITED STATES PATENT OFFICE.

FREDERICK A. TEGELER, OF LA GRANGE, ILLINOIS.

RAIL-DRILLING DEVICE.

Application filed December 29, 1919. Serial No. 343,002.

To all whom it may concern:

Be it known that I, FREDERICK A. TEGELER, a citizen of the United States, and a resident of La Grange, in the county of Cook and State of Illinois, have invented a new and useful Improvement in a Rail-Drilling Device, of which the following is a description, reference being had to the accompanying drawings, which form a part 10 of my specification.

My invention relates to a power drill more especially intended and adapted for drilling railroad rails and simultaneously providing the rails with a plurality of holes 15 arranged at predetermined and uniform distances apart.

One object of my invention is to provide a device of the character mentioned which is adapted to be transported along the rails, 20 optionally, through the medium of its own power; and which at the same time is adapted to be readily removed from the rails, when occasion requires, by a single operator and wheeled away from the track.

Another object of my invention is the provision of a device wherein the drills may be readily disengaged from the rails and the drill mechanism or frame easily swung or moved into inoperative position and into 30 more or less compact relation by a single operator and thereby enable the more convenient handling, transportation and storage of the device.

A further object of my invention is to provide improved means for suspending the 35 drill mechanism beyond or rather to the outside of the rail, in order that the holes will be drilled from the outside of the rail, as is especially preferable when drilling for 40 the purpose of bonding the track for a track circuit.

A further object of the invention is the provision of improved means whereby the drills, *per se*, are held in place and the 45 drills fed to the work; while at the same time providing a construction wherein the weight of the drill mechanism will be carried or suspended from the truck or supporting structure in such manner that the 50 device may be easily removed from the track by a single operator; and furthermore, wherein the drill mechanism can be readily disconnected from the supporting structure or truck so as to permit the use 55 of said truck as a light motor track-car.

The foregoing enumerated objects and ad-

vantages, as well as other advantages, will be more fully comprehended from the following detailed description of the accompanying drawings, wherein: 60

Figure 1 is a side elevation of my improved device illustrated in place on a track and in drilling position.

Figure 2 is a side elevation of the same, showing the drill mechanism or frame moved 65 into inoperative position, ready to be removed from the track.

Figure 3 is a top plan of my device, shown in place on a track and in drilling position. 70

Figure 4 is an enlarged plan, partially in section, of the multiple hole drill mechanism and operating gears; with some of the drills shown disposed through the web of the rail. 75

Figure 5 is a partial side and sectional elevation taken on the line 5—5 of Figure 4, looking in the direction of the arrows.

Figure 6 is a detail view of the power shaft coupling, illustrating the same in coupled relation. 80

Figure 7 is a detail of the same mechanism, partially in section; the view being substantially on the line 7—7 of Figure 6, looking in the direction of the arrows. 85

Figure 8 is a similar view, except that the mechanism or shaft coupler is shown in detached or non-coupled relation.

Figure 9 is an end elevation of the same, looking at the right hand side of Figure 6. 90

Figure 10 is a side elevation of the drill-feed and clamping mechanism, illustrating same in drill-advanced and clamping position.

Figure 11 is a similar view illustrating 95 the mechanism in drill-retracting position.

Figure 12 is a similar view showing the mechanism in complete drill-retracted and rail-releasing position.

Figure 13 is a detail view of portions of 100 the clamping and feed levers.

Figure 14 is a view taken on the line 14—14 of Figure 3, looking in the direction of the arrows.

Figure 15 is a detail sectional view of 105 clutch mechanism employed in connection with the balance wheel.

In the particular exemplification of the invention, the device comprises a suitable truck which consists of the main frame 110 members 20, suitably spaced apart and secured together to receive the main support-

ing wheels 21 therebetween, whereby the truck may be transported along the rails. Secured to the main frame members 20 in any suitable manner, and at opposite ends 5 of the truck, are cross-members or bars 22, which are disposed transversely of the track and have their free or opposite ends provided with stub-axles 23 on which the small wheels 24 are rotatably mounted; the wheels 10 24 traveling on the adjacent rail of the track.

The main supporting wheels 21 are rotatably mounted on journals or axles secured in any suitable manner to the main frame members 20. Disposed beyond one side of the main frame are a pair of ground wheels 25 rotatably mounted on shaft 26 which is supported by the links or arms 27 secured at opposite ends of the main or truck frame. 15 The links or arms 27, in turn, are pivotally secured to the main frame at 28 so as to adapt them to oscillate in a vertical direction, see Figures 1 and 2. The shaft 26 is also supported by means of link 29 which is 20 pivotally secured at 30 to a bell-crank 31, the center whereof is pivotally secured at 32 to the main frame or truck. As is evident from the construction shown in Figure 2, when the bell-crank 31 is rotated about 25 the pivotal point 32 into the position illustrated in Figure 1, the pivotal mounting of link 29, on crank 31, will cause the shaft 26 with the ground-wheels 25 to be elevated out of ground-contacting position into the position shown in 30 Fig. 1. The ground-wheels 25 are disposed at right angles to the main frame and therefore to track-wheels 21, so that when the ground-wheels are lowered into the position 35 shown in Figure 2, the opposite or drill mechanism-carrying side of the device may be lifted up from the track so as to support the device on the ground-wheels 25 and in turn cause the main wheels 21 to be moved 40 out of traveling contact with the rails thereby permitting the device to be transported away from the track when occasion requires.

The power for operating my improved 50 device comprises any suitable internal combustion motor, indicated at 33, which is mounted on the main frame of the truck; with the crank-shaft of the motor connected with a suitable sprocket, as shown at 34. 55 One of the main supporting wheels 21 of the truck is shown provided with a large sprocket 35, see Figure 3; the sprocket wheel 35 being adapted to receive a suitable sprocket-chain which is to be disposed about 60 the sprocket 34 when it is desired to use the power or motor for propelling the device along the track.

At a suitable point, intermediate of the 65 ends of the main cross-bars or frame members 22, I provide suitable brackets or jour-

nal-boxes, as at 36, for oscillatingly securing the frame 37 of the drill mechanism through the medium of mechanism later to be described; the mounting of the frame 37 in the manner shown and to be described, 70 permits the drill mechanism and said frame to be swung vertically from the operative position shown in Figure 1 into the inoperative position shown in Figure 2 where the drill mechanism will be disposed above the 75 main truck portion of the device. The journal or supporting rod 38 of the drill mechanism frame 37 is shown provided with the segmental grooved wheels 39 fixedly secured thereto; and the grooved segmental wheels 80 39, at one point, each have a chain 40 secured thereto, the opposite end whereof is connected with coil springs 41 whose opposite ends are fastened to the main supporting frame 20 and constantly exert a 85 pulling tension on the chains 40 and therefore on the segmental wheels 39 so that the frame 37 of the drill mechanism will be more or less yieldingly suspended in either position and most of the weight of the drill 90 mechanism taken up by said springs. The chains 40 are secured to one end of each segment so that when the drill mechanism is in drilling or operative position a pulling tension will be exerted on the end of the 95 segments 39 disposed above the journal or rod 38 of the frame 37 and thus tend to yieldingly support the weight of the mechanism. It is evident from the construction shown and described that swinging of the 100 drill into inoperative position, as shown in Figure 2, will move the segmental wheels through the arc of a circle so that the respective springs 41 will exert tension on the end of segments 39 which are now disposed below the journal of the drill-frame mechanism and thus tend to carry the major portion of the weight of said frame when the latter has been folded over the truck, as 105 shown in Figure 2; the springs thus tending 110 to assist the operator in swinging the drill mechanism into and out of operative position; while the feed-lever carried by the frame may be used by the operator as a handle in swinging the frame into inoperative 115 position. In order to support the drill mechanism frame when in folded over position, shown in Figure 2, I provide the main frame with suitable brackets, as at 42, see Figure 3, formed so as to receive the frame 120 members 37. The main frame members 22 are reenforced by the cross-members 43, see Figure 3, secured at a point adjacent the stub-axle end thereof and preferably in the somewhat forwardly bowed manner, shown 125 in Figures 1 and 2, so as to serve as a handle when it is desired to lift the small wheel side of the device off the track.

The power-imparting shaft for the drill mechanism is illustrated at 44, see Figure 130

3, and is preferably made sectional, with two sections secured together by means of a suitable knuckle joint, as at 45, with the pins or pivot points of the joint 45 arranged 5 in alignment with the journal-boxes 36 which constitute the pivot points for the drill mechanism frame 37. This construction enables one section of the shaft 44 to swing through the arc of a vertically disposed circle when the drill mechanism is 10 swung into and out of operative position; the outer shaft section being also supported by a suitable box or bracket 46 which is fastened on the rod 38 of the drill-frame and thus tends to hold the shaft section in proper 15 position at all times; the inner or non-swinging shaft sections being supported in a suitable frame, as at 47, secured to the main frame of the truck. The end of the inner section is provided with a detachable 20 coupling whereby this shaft section 44 is placed in operative relation with the sprocket 34 secured to the crank-shaft 48 of the motor. The coupling is shown in detail in Figures 6, 7, 8 and 9 and comprises a plate 49 which is provided with a hub 50 preferably formed integral therewith and secured to the shaft-section 44 so as to rotate therewith, as for example by means 25 of pin 51. The plate 49 is provided with a series of circumferentially disposed holes or openings therethrough which correspond in number and location with the spaces intermediate of the teeth of the sprocket wheel 34; it being understood that the sectional drive 30 shaft 44 is disposed in horizontal alignment with the crank-shaft 48 and with the sprocket 34 on the crank-shaft in close proximity to the plate 49 which is secured to the end of the drive shaft section 44. A second 35 plate 52 is slidably mounted on the elongated hub 50 of plate 49 and therefore on the side of plate 49 removed from the side adjacent sprocket wheel 34. The plate 52 is provided with a series of circumferentially disposed studs or pins 53 of predetermined diameter and length and arranged 40 in alignment with the respective holes in plate 49, so that when plate 52 is brought 45 into juxtaposition with plate 49, the studs or pins 53 will be disposed through the holes in plate 49 a distance sufficient to extend into the spaces intermediate of the teeth of sprocket 34, see Figures 6 and 7. 50 It is evident that when the elements are in the relation just described, and as shown in Figures 6 and 7, that the drive shaft section 44 will be operatively connected with the crank-shaft 48 so that power, during 55 operation of motor 33, will be transmitted through the sectional drive shaft 44 to the drill mechanism. On the other hand, when the plates 49 and 52 are in the separated relation shown in Figure 8, the studs or pins 53 will have been sufficiently retracted 60 so as to move them out of interlocking relation with the sprocket 34 and thus cause an uncoupled or detached relation between the crank-shaft and sectional drive shaft. In order to maintain the various positions of plate 52, relative to plate 49, I provide plate 52 with latch members 54 slidably mounted on the side face of plate 52 and normally held in contact with the elongated hub 50 of plate 49 by means of suitable springs 55. The hub 50 at suitable points is provided with grooves 56 and 57 adapted to receive latch members 54 when plate 52 has been moved to either one of its extreme positions; that is to say, groove 56 will receive the latch members 54 and maintain plate 52 in juxtaposition with plate 49, and therefore with the studs or pins 53 in operative relation with sprocket 34; while groove 57 will receive latch members 54 and maintain plate 52 in its retracted position, as shown in Figure 8.

The drive shaft section 44 is shown provided with a suitable balance wheel at 58; and this shaft section is also provided with a suitable pulley 59 adapted to receive a suitable belt for operating a rotatably mounted fan 60 whereby a current of air is induced for cooling motor 33.

The sectional drive shaft 44 is also provided with a suitable clutch controlling member at 61 for actuating any suitable clutch mechanism, as for example the clutch mechanism disclosed in Figure 15 and contained in the balance wheel 58 whereby the adjacent drive shaft sections may be coupled together and power transmitted to the outer section of said sectional shaft 44 when the coupling mechanism, shown in Figures 6 to 9, has been moved into operative position.

The end of the outer section of the sectional drive shaft 44 is provided with a suitable worm reduction gear at the point 62; the worm gear being enclosed in the housing, as shown, which housing or casing is adapted to contain suitable lubricant wherein the gear may be constantly emersed. The worm within casing 62 is adapted to rotate shaft 63 on which sprocket wheel 64 is secured so as to rotate therewith. The shaft 63 is supported by suitable supporting members 65 which maintain the position of shaft 63 relative to the drill-operating mechanism hereinafter described. The lower end of the supporting members 65 are provided with suitable boxes 66 in which the main operating shaft 67 is rotatably mounted. The sprocket 64 is shown provided with a sprocket chain 68 which takes about a sprocket wheel 69 secured to drill shaft 67 so as to impart rotation thereto. As my improved device is intended to simultaneously drill a plurality of holes, the drill shaft 67 is shown provided with a number of beveled gears 70 arranged in pairs

at opposite ends thereof, with the gears of each pair maintained in proper spaced relation by means of a suitable collar 71, see Figure 4; and the shaft 67 is fitted with suitable anti-friction bearings at 72 for taking up the end thrusts on shaft 67. The bevel gears 70 each mesh with a bevel gear 73 secured to the ends of the drill spindles 74; the gears 73 being so secured to the drill 10 spindle 74 as to permit slight endwise movement; while the end thrusts on the drill spindle will be taken care of by suitable ball bearings, as shown at 75. Each drill spindle 74 is tapped at the end of the drill socket 15 and provided with a screw as at 76 which enables the respective drill-bits 77 to be adjusted to the same length or distance relative to the rails; and the drill-bits in turn are held in place by any suitable mechanism, 20 as for example the set-screw 78.

As previously stated, my improved rail drilling device is especially intended for simultaneously drilling a multiple of holes at fixed distances apart and the drills are 25 arranged in pairs at opposite ends of the device as shown; with each pair of drills and operating mechanisms encased in separate casings 79, 79 of the open or more or less skeleton formation shown in Figures 3 30 and 4, whereby the drill-spindles, mitre or bevel gears and thrust bearings are all enclosed. The casings 79 are supported from the drill frame members 37 by means of suitable brackets or hangers 80, which may 35 be bolted or otherwise secured to the casings 79, and these brackets or hangers are provided with rollers 81 arranged in vertical spaced relation to ride along the top and bottom of frame member 37, see Figure 5. 40 With this arrangement the drill mechanisms are not only properly supported, but the drill-casings and the drills may also be readily moved lengthwise of the frame 37 toward and away from the adjacent rails, during 45 drilling operation; and the frame members 37 may be provided with suitable stops or pins as at 82, adapted to prevent the too far movement of the drill-casings in either direction.

50 The drill-casings 79 are shown provided with rearwardly disposed portions 79^a formed to provide suitable bearings for a preferably hollow shaft 83. The opposite ends of shaft 83 are each provided with a 55 crank-arm 84, apertured to receive a shaft 85, the ends whereof are disposed through the crank-arms 84 at opposite ends of shaft 83 so as to permit rocking of shaft 85. The shaft 85 in turn has a crank-arm 86 rigidly 60 secured on each end thereof; with one of said crank-arms made integral with a lever 87, whereby shaft 85 and the crank-arms 86 may be rocked and oscillated into any one of the various positions shown in Figures 65 10 to 12. The free ends of the crank-arms

86, each have a feed-hook or rail-gripping member 88 pivotally secured thereto by means of the stud-bolts 89. At a point intermediate of its ends, the shaft 83 is provided with flanged collars or lever guides 90, 70 rigidly secured thereto and adapted to receive a lever 91 therebetween; the guides, or at least one of them, being notched at prearranged points as shown in Figures 10 to 12, for the purpose of receiving the 75 spring-controlled latch 92, secured to the lever 91 and thereby establish operative relation between the lever 91 and the shaft 83.

The feed-hooks or rail-engaging members 88 are so formed that they will contact with 80 the opposite or inside of the rail, a distance below the horizontal plane of drills 77, substantially equal to that of the pivot point 89 below the center of the fulcrum point of feed-lever 91, namely the center of shaft 83 85 and thereby providing a straight drilling feed thrust and eliminating unnecessary friction and at the same time permitting proper and true operation of the drills. The feed-hooks 88 are shown provided with clips 90 93 through which a rod 94 extends; the rod extending likewise of the device so as to be disposed through the clips 93 on both feed-hooks 88 at opposite ends of the machine. The rod 94 is threaded at its ends and provided with nuts whereby the clips 93 are firmly clamped at the desired point on the hooks 88. The rod 94 is also provided with guides 95 loosely mounted on frame members 37; the guides 95 serving to hold the 100 hooks 88 in proper alignment.

Each crank-arm 84 has a rod 96 pivotally secured on the inner side thereof; the rods 96 being bent to take over the shaft 85 and beneath the rear enlarged portion of casings 105 79 and thence back into substantially the same horizontal plane as the pivotal point thereof on crank-arms 84, as shown in Figures 10 to 12. The forward ends of the rods 96 are slidably mounted in lugs on the 110 sides of the casings 79, whereby the rods are supported in proper horizontal position when the mechanism is in operative position. The forward ends of the rods 96 are shown threaded and provided with the adjustable 115 heads or tips 97^a, which permit the tips to be adjusted lengthwise of the rods 96 so as to adapt them to long or short drill-bits; the tips 97^a being locked in adjusted position by means of nuts 98^a. The push-rods are 120 also shown adjustable by means of turnbuckles 97 which latter are locked by means of nuts 98. The rods 96 are intended to have approximately the same length of stroke as the drills, but are intended to move in the 125 opposite direction and are caused to push against the rails when the drills are being withdrawn from the drilled holes in the webs of the rails.

The crank-arms 84 are shown provided 130

with laterally disposed lugs 99 on the sides provided with cranks 86 and the integral lever 87; and these lugs 99 are provided with adjustable set screws 100. The set-screws 100 are intended to control the limit of movement of cranks 86 when in clamped position and also to control the length of drilling stroke; the set-screws 100 controlling the distance between centers of stud-bolts 89 and shaft 83; because in shortening the distance between centers as described will shorten the length of drill-stroke and produce an easier feed.

From the construction shown and described, it is apparent that when lever 91 is oscillated to the left, as in Figure 10, shaft 83 will be rocked so as to move cranks 84 into the downwardly presented position shown in Figure 10, which, in turn, carries 20 the pivotal point of crank 86 and lever 87 downwardly, thereby moving the free end of crank 86 with stud-bolt 89 into contact with set-screw 100, thus retracting the feed-hooks 88 and bringing the hook ends into 25 clamping engagement with the web of the rail on the side opposite to that of the drills.

With the feed-hooks 88 positioned as just described, the operator exerts a forward pressure on lever 91 (which forward pressure has a tendency to induce further rocking of shaft 83 so as to tend to swing the free end of crank 84 further to the right) so as to force the drill mechanism, namely the casings 79 and the drills, toward the 35 rail; such forward pressure being maintained until the drilling operation is complete as shown in Figure 10.

The drilling operation having been completed, the operator then oscillates lever 91 toward the right in Figure 10 into the position shown in Figure 11. This operation rocks shaft 83 sufficiently to oscillate crank 84 to which push-rods 96 are pivotally secured by means of cap-screws 103, which 45 screws are substantially aligned with stud-bolts 89, thereby producing the same length of stroke in the opposite direction to that of the drills, thereby bringing the push-rod 96 against the web of the rail and thus exerting a retracting action on the drill mechanism, which places it into the position shown in Figure 11.

In order to transport the device to the next joint of the rail or point of drilling 55 operation, the operator then oscillates lever 87 from the position shown in Figure 11 into the position shown in Figure 12, thereby swinging crank 86 forwardly and causing feed-hooks 88 to be moved out of clamping 60 relation with the rail. The forward movement of the feed-hooks, as described, brings the clips or clamp members 93 against the ball of the rail, thereby preventing any further forward movement of the 65 hooks 88, with the result that the exerted

pressure on the lever 87 will cause the entire drill mechanism to be moved rearwardly along the drill frame 37, a distance sufficient to have the drill-bits and push-rods clear the ball of the rail (as shown in Figure 12) 70 in the event that it is desired to elevate the drill mechanism and drill frame into transporting position. Where the device is merely to be transported along the rails, and circumstances make it advisable to maintain the ground-wheels in their maximum elevated position, it may be desirable to provide some means, as for example a proper hook and chain, for holding the ground 75 wheels completely elevated. 80

In order to lubricate and cool the drill-bits during operation, I provide a suitable lubricant holder 104 mounted at a suitable point on the frame and provided with flexible conduits or hose, as shown at 105 in 85 Figure 3, which convey the lubricant and cooling medium to the pipes or conduits 106 which are slidably mounted on the drill casings 79 in suitable guides 107; it being understood that one conduit is provided for 90 each drill casing. The inner or forward ends of the conduits 106 are branched so as to convey the lubricant or cooling medium to each drill-bit; the branches terminating in suitable nozzles which are each provided 95 with a suitable valve as shown at 108. The conduits 106 are suitably clamped to the push-rods 96, by means of straps 109, so as to maintain the nozzle-end of said conduits in proper relation with the rail during 100 the drilling operation. The straps at 109 are secured to push-rods 96 forward of turn-buckles 97, so that adjustment of push-rods 96 by means of the turn-buckles 97 will also cause the conduit 106 to be adjusted 105 in a similar manner so as to constantly maintain the proper relation thereof relative to the rail.

The conduits 106 are each provided at a suitable point with a valve as at 110, which is operated by means of a stem 111, connected by rod 112 to the rod 94. The valve and its stem are so positioned that when the feed-hooks 88 are in clamping position, the valve 110 will be in open position and permit the lubricant or cooling medium to pass forward to the nozzles and be discharged if valves 108 are open. It is evident that when the feed-hooks are moved into clamping position (see Figure 12) through mechanism as heretofore described, the valve 110 will be automatically closed and the flow of lubricant or cooling medium automatically shut off, thus preventing any waste of the fluid during non-drilling operation. 110

A lever 113 is suitably secured to the main frame so as to be in easy reach of the operator handling lever 91. The main portion of lever 113 is adapted to control the clutch 61 by means of connecting rods 114 130

through the medium of bell-crank 115; while the latch portion 116 of the lever is adapted to control the motor.

The feed-hooks 88 are preferably made 5 adjustable longitudinally by making same in two sections, as more clearly shown in Figure 4. The abutting surfaces or overlapping ends of the two portions or sections of the feed-hooks are provided with serrations, as at 88^a, while one of the sections or portions is provided with a pair of slots disposed lengthwise, adapted to receive the bolts 88^b. With this construction, when the nuts on the bolts 88^b are screwed up, the 10 two sections will be firmly clamped together and lengthwise movement between them prevented by the serrations or gripping surfaces 88^a. This enables the feed-hooks to be lengthened or shortened commensurate 15 with the length of the drill-bits, in addition to the adjustment made possible by the plurality of holes at the end of the feed-hooks.

The ends of the journal or supporting rods 38, preferably at points beyond the 20 frame members 22, are provided with crank-arms 101 to which suitable connecting means 102, such as cables or rods are secured; the connecting means 102 being also secured to the ends of the bell-cranks 31 25 disposed at each end of the device.

With this construction, it is evident that when the drill frame 37 is elevated, the 30 crank-arms 101, through the medium of the grooved segmental wheels and journal 38, will be oscillated in such manner as to release the connecting means 102 and thus permit the ground-wheel frame and therefore 35 also the wheels, to descend and bring the wheels into contact with the ground. On the other hand, when the drill-frame is 40 lowered into operating position, the crank-arms 101 will exert a pull on the connecting means 102 and thereby oscillate bell-crank 31 and cause the ground-wheels and their 45 frame to be elevated into the position shown in Figure 1, thus providing clearance beneath the ground-wheels sufficient to pass over the ends of ties, switches and road-crossings.

The drill-casings 79 are so constructed 50 that they may be filled with lubricant and the gearing and mechanisms within constantly kept properly lubricated.

In order that the drilling operations may 55 be entirely controlled from the drill-mechanism side of the device, I prefer that sectional drive-shaft 44 be extended as shown beyond the worm-casing 62 in order that the end of the shaft 44 may receive a suitable crank for the purpose of cranking or 60 starting the motor 33.

My improved device is so constructed that the entire drill-frame and the mechanisms carried thereby, including the sectional

drive-shaft, may be readily removed or 65 disconnected from the main or truck-frame when it is desired to use the device as a motor track car or to substitute a different type of drilling mechanism. For this reason I prefer to employ the coupling mechanism 70 specifically illustrated in the detail Figures 6 to 9, whereby the inner end of the sectional drive-shaft 44 may be removed from its supporting frame 47 after the coupling elements have been disconnected from sprocket 75 34, which sprocket is then provided with a suitable sprocket chain which is also disposed about the sprocket 35 secured to the axle of one of the main truck or track-engaging wheels 21. With this arrangement, 80 it will be seen that all unnecessary parts can be removed and the full power of the motor transmitted to the drive-wheel of the truck; while on the other hand, a suitable drill-frame and drilling mechanism may be 85 readily secured to the truck-frame when desired; the application and removal of the drill-frame 37 and the drilling mechanisms carried thereby being accomplished by simply removing the journal-boxes or brackets 90 36, detaching springs 41 from the truck-frame and disconnecting the inner section of the sectional drive-shaft 44 as previously described. As is apparent, therefore, the same truck may be employed in conjunction 95 with the type of drill-frame and mechanism which is shown and described in a copending application, thereby obviating the necessity for providing a number of truck-portions of the class described for different 100 drilling mechanisms.

I have shown and described what I believe to be the simplest and best adaptation of my invention; but it is apparent that certain modifications may be made in details 105 of construction without, however, departing from the spirit of my invention.

What I claim is:—

1. A rail drilling device of the class described, comprising a truck provided with motive power, a drill-frame hingedly secured to said truck and adapted to be disposed to the outside of the rail when in operative position and to fold across said truck toward the opposite side when in transporting position, drill-casings carried at the outer end of said frame and movable thereon and power-imparting means leading from the motive power on said truck to said drill-casings, said means having a yielding point in alignment with the hinged point of said drill-frame so as to fold therewith.

2. A rail drilling device of the class described, comprising a truck provided with motive power, a drill-frame hingedly secured to said truck so as to be disposed to the outside of the rail when in operative position and to fold upwardly across said

truck toward the opposite side thereof when in transporting position, yielding means intermediate of the truck-frame and said drill-frame for yieldingly supporting the weight 5 of said frame and to assist in the vertical movement thereof, drill-casings carried at the outer end of said drill-frame and movable thereon, and power-imparting means leading from the motive power on said truck 10 to said drill-casings, said means having a yielding point in alignment with the hinged point of said drill-frame so as to fold therewith.

3. A rail drilling device, comprising a 15 truck-frame, a drill-frame pivotally secured on said truck-frame to swing through the arc of a vertically disposed circle and between the truck-wheels at one side of the truck-frame so as to extend beyond the rail multiple 20 drill mechanism slidably mounted on the free end of said drill-frame and adapted to be disposed to the outside of the rail, and means whereby the degree of movement of the drill mechanism along the drill-frame 25 is determined.

4. A rail drilling device, comprising a four-wheeled truck provided with transversely disposed frame-members at opposite ends, a drill-frame provided with a journal 30 rotatably secured to said frame-members to adapt the drill-frame to swing upwardly and onto the truck into inoperative position and downwardly beyond one side of the truck so as to have the free end of said 35 drill-frame disposed on the outside of the rail, means secured to the drill-frame and to the truck whereby the former is yieldingly suspended and the weight transmitted to the opposite side of the truck, and multiple 40 drill mechanism slidably mounted on the free end of said drill-frame.

5. A rail drilling device, comprising a motive power truck adapted to travel on the rails, a drill-frame journaled on said truck 45 so as to swing upwardly onto the truck into inoperative position and downwardly beyond one side of the truck into operative position, multiple drill-mechanism slidably mounted on the free end of said drill-frame, a sectional drive-shaft intermediate of the motive power of the truck and said drill mechanism for transmitting power to the latter, said drive-shaft being provided with a knuckle-joint at a point in alignment with 50 the journal of said drill-frame to permit vertical movement of the outer section of said drive-shaft with the drill-frame, and means for yieldingly supporting the drill-frame from the opposite side of the truck 55 and to assist in the vertical movement of the drill-frame.

6. A rail drilling device, comprising a truck, a drill-frame journaled on said truck to swing through the arc of a vertically dis-

posed circle and extend beyond one side of 65 the truck to the outside of the rail when in operative position and onto the truck into inoperative position, multiple drill mechanism slidably mounted on the free end of said drill-frame, ground-wheels hingedly secured to the opposite side of the truck, and means whereby the position of the ground-wheels is controlled by the position of the drill-frame.

7. A rail drilling device, comprising a 75 truck, a drill-frame journaled on said truck at a point intermediate of the sides of the truck so as to swing through the arc of a vertically disposed circle and extend beyond the side of the truck to the outside of the rail 80 when in operative position and onto the truck toward the opposite side thereof when in inoperative position, the journal of said drill-frame being provided with radiating or crank portions, means secured to the radiating or crank-portions of the drill-frame journal and to the opposite side of the truck for yieldingly supporting the drill-frame and to assist vertical movement thereof, drill-mechanism mounted on the free end 90 of the drill-frame, and ground-wheels hingedly secured to the opposite side of the truck.

8. In a rail drilling device, a plurality of 95 slidably mounted drill-casings, arranged in horizontal spaced relation, a plurality of drill-spindles rotatably mounted in each drill-casing, a single power-imparting shaft disposed transversely through the drill-casings and common to all of the drill-spindles, 100 a rock-shaft disposed transversely of and mounted at the rear ends of said drill-casings, feed-hooks pivotally mounted at their rear ends and adapted to engage with the side of the rail opposite to that on which 105 said drill-casings are located, means intermediate of said rock-shaft and the feed-hooks and controlled by said rock-shaft whereby the feed-hooks are simultaneously forced into rail-engaging position when said 110 shaft is rocked in one direction, and means whereby said shaft may be rocked and with the drill-casings forced in directions toward and from the rails.

9. In a rail drilling device, a plurality of 115 slidably mounted drill-casings, a plurality of drill-spindles rotatably mounted in each drill-casing, a single power-imparting shaft common to all of the drill-spindles, a rock-shaft mounted in said casings, said 120 rock-shaft being provided with crank-arms, feed-hooks pivotally secured to said crank-arms and adapted to be forced into rail-engaging position thereby when the rock-shaft is rocked in one direction, means whereby 125 the rock-shaft is actuated and the feed-hooks maintained in clamping relation with the opposite or free side of the rail, and means se-

cured to crank-arms adapted to be forced against the adjacent or near side of the rail when said rock-shaft is rocked in the opposite direction and the drill-bits thereby 5 forced away from the rail.

10. In a rail drilling device, a plurality of slidably mounted drill-casings, a plurality of drill-spindles, rotatably mounted in each drill-casing, a single power imparting shaft 10 common to all of the drill-spindles, a rock-shaft mounted at the ends of said drill-casings in substantially the same horizontal plane as said drill-spindles, the ends of the rock-shaft terminating in crank-arms, feed-hoops having movable pivotal connections at their rear ends with said crank-arms and adapted to engage with the far or opposite side of the rail when the rock-shaft is rocked in one direction, the relation between the 15 crank-arms and feed-hoops being such that the rail-engaging ends and the connected ends of said feed-hoops will be so disposed, relative to the drill-spindles when the rock-shaft is rocked in one direction, that straight 20 drilling thrusts will be provided, and means whereby the rock-shaft may be actuated and the drill-casings with the free ends of the feed-hoops forced, respectively toward the rail on opposite sides.
- 25 11. A rail drilling device, comprising a truck-frame, a drill-frame journalled on said truck-frame at a point intermediate of opposite sides to permit the drill-frame to swing vertically beyond one side of the truck-frame or upwardly onto the other side 30 of the truck-frame to shift the center of gravity, radius members secure to the journal of said drill-frame, and tension means connected with said radius members to 35 yieldingly hold the drill-frame in its suspended positions.

- 40 12. A rail drilling device, comprising a truck-frame, a drill-frame, journalled on said truck-frame at an intermediate point so as 45 to permit the drill-frame to swing vertically beyond one side and into a plane beneath that of the truck-frame or upwardly over onto the opposite side of the truck-frame, and counterbalancing means secured 50 to the drill-frame journal and connected with the truck-frame whereby the drill-frame is yieldingly suspended in operative position from the truck-frame, the drill-frame journal and said counter-balancing 55 means being detachable from said truck-frame, thereby to disconnect the drill-frame from the truck-frame.

- 60 13. A rail drilling device, comprising a truck-frame, a drill-frame journalled on said truck-frame, ground-wheels mounted on the side of the truck-frame opposite to that of the drill-frame, and means intermediate of the drill-frame journal and said ground-wheels whereby the latter are elevated when

the drill-frame is lowered into operative 65 position.

14. A rail drilling device, comprising a truck-frame, a drill-frame journalled at an intermediate point on said truck-frame, so as to swing through the arc of a vertically disposed circle toward one side of the truck-frame, ground-wheels pivotally mounted on the side of the truck-frame opposite to that toward which the drill-frame is adapted to swing, means whereby the ground-wheels are held in ground-engaging position when said wheels have been lowered, and means intermediate of the ground-wheels and said drill-frame whereby the ground-wheels are elevated when the drill-frame is swung 80 downward into operative position.

15. A rail drilling device, comprising a motive power truck adapted to travel on the rails, a drill frame journalled on said truck so as to swing through the arc of a vertically disposed circle toward one side of the truck, drill mechanism mounted on the free end of said drill-frame, a sectional drive-shaft intermediate of the motive power of the truck and said drill-mechanism, some of the sections of said drive-shaft being provided with a knuckle-joint at a point in alignment with the journal of said drill-frame, and means intermediate of a third section of said drive-shaft and the motive power of the truck whereby operative relation between the sectional drive-shaft and the motive power may be established.

16. A rail drilling device, comprising a motive power truck provided with a power-imparting sprocket-wheel, a drill-frame journalled on said truck to swing through the arc of a vertically disposed circle, drill-mechanism mounted on said drill-frame, a sectional drive-shaft intermediate of said sprocket-wheel and the drill-mechanism, the sectional drive-shaft being provided with a flexible connection at a point in alignment with the journal of the drill-frame on the truck, and means slidably mounted on one section of the sectional drive-shaft adapted to have interlocking relation with said sprocket-wheel.

17. A rail drilling device, comprising a motive power truck provided with a power-driven sprocket, a drill-frame journalled on said truck to swing through the arc of a vertically disposed circle toward one side of said truck, drill-mechanism mounted on said drill-frame, a sectional drive-shaft intermediate of said sprocket and said drill-mechanism, the drive-shaft being provided with a flexible connection at a point in alignment with the journal of said drill-frame, means slidably mounted on one of the sections of said sectional drive-shaft and adapted to effect operative relation

with said sprocket, and means whereby said last mentioned means may be locked in coupled or uncoupled position.

18. A rail drilling device, comprising a motive power truck provided with a power-imparting sprocket, a drill-frame journaled on said truck so as to swing through the arc of a vertically disposed circle toward one side of the truck, drill-mechanism mounted on said drill-frame, a sectional drive-shaft, means whereby the drive-shaft may be coupled to said sprocket, the outer section of said drive-shaft being provided with a gear-casing, and means whereby the operative relation between the drive-shaft and the drill-mechanism is maintained.

19. In a device of the class described, a truck-frame, a drill-frame pivotally mounted between opposite sides of the truck-frame so as to swing vertically toward one side of the rail beyond the side of the truck-frame or upward onto the opposite side of the truck-frame to shift the center of gravity, means whereby said drill-frame is yieldingly supported, multiple drill mechanism slidably mounted on said drill-frame, said drill mechanisms comprising a drill-spindle and a drill-bit, and means disposed at the end of each drill-spindle whereby all of said drill-bits may be adjusted so as to be aligned relative to the rail to be operated on.

20. In a device of the class described, a drill-frame, drill-casings slidably mounted on said frame, means rotatably mounted on the drill-casing and comprising a plurality of members having pivotal relation with each other, and feed-hooks carried by one of said members and adapted to engage with the adjacent rails when said means are rotated in one direction, the member provided with the feed-hooks being arranged to have independent rotation whereby the feed-hooks may be given additional longitudinal movement so as to clear the tops of the rails.

21. In a device of the class described, a drill-frame, drill-casings slidably mounted on said drill-frame, compound means oscillatingly carried by the drill-casings and comprising a pair of cam-members, one of which is rotatably mounted on the drill-casing, while the other is eccentrically mounted on the first mentioned member, and feed-hooks pivotally mounted on the second mentioned cam-member and adapted to engage with the opposite side of the rails operated on, the relation between the pivotal points of the feed-hooks and the point of engagement on opposite sides of the rail being such that a straight drilling thrust will be provided.

22. In a device of the class described, a drill-frame, drill-casings secured on said frame so as to move horizontally toward

and away from the rails, means carried by the drill-casings and arranged to be oscillated, rail-engaging members carried by a part of said means and adapted to engage with the opposite side of the rail when said means are oscillated in one direction and the drill-casings forced toward the rail, and push-rods carried by said first means adapted to engage the adjacent side of the rail when the first means are oscillated in a direction to release said rail-engaging members, whereby the drill-bits will be forced away from the rail.

23. In a device of the class described, a drill-frame, drill-casings suspended from said frame so as to slide lengthwise of the frame in a horizontal direction, means whereby the extent of movement along the drill-frame will be determined, oscillatingly mounted means, carried by the drill-casings, having a portion adapted to form gripping relation with the rails when a part of said means is oscillated in one direction, and push-rods carried by said second means and adapted to engage with the near side of the rail when a part of said second means is oscillated in the opposite direction and the drill-casings thereby forced away from the rail, said push-rods being adjusted longitudinally.

24. In a device of the class described, a drill-frame, drill casings suspended from said frame so as to move lengthwise thereof, said drill-casings being provided with rotatable drill-spindles having drill-bits adjustably secured at their outer ends, means whereby all of said drill-spindles are simultaneously operated, the drill-casings being provided with a rock-shaft disposed transversely thereof, the outer ends of said rock-shaft being provided with crank-arms, a second rock-shaft disposed through the free ends of said crank-arms and adapted to be oscillated thereby, the outer ends of said second rock-shaft being provided with crank-arms rigidly secured thereto, feed-hooks pivotally secured to the free ends of the crank-arms of said second rock-shaft, the feed-hooks being adapted to engage with the opposite side of the rail, and means adapted to have operative connection with the first mentioned rock-shaft whereby the drill-casings with the drill-spindles may be forced toward the rail, said rock-shaft rocked and the second rock-shaft oscillated so as to force the feed-hooks into rail-gripping position.

25. In a device of the class described, a drill frame, drill-casings slidably mounted on said frame, the drill-casings being provided with drill-spindles having adjustable drill-bits at the outer ends thereof, a rock-shaft carried by said drill-casings and having its outer ends provided with crank-arms, a second rock-shaft carried by said crank-

arms so as to oscillate therewith, the outer ends of said second rock-shaft being provided with crank-arms rigidly secured to said shaft, one of said crank-arms being provided with an operating lever whereby the crank-arms and said second rock-shaft may be given movement independent of that given by the crank-arms of the first mentioned rock-shaft, feed-hooks pivotally secured to the crank-arms of the second rock-shaft and adapted to engage with the opposite side of the rails, the pivotal points of the feed-hooks, axis of the first mentioned rock-shaft and the point of contact of the feed-hooks with the rails being so correlated that a straight drill-thrust will be provided, push-rods pivotally secured to the crank-arms of the first mentioned rock-shaft and adapted to move into pushing engagement with the rails when the drill-bits are being withdrawn, and means having operative connection with the first mentioned rock-shaft whereby the drill-casings may be forced toward the rails and the respective rock-shafts actuated.

26. In a device of the class described, a drill frame, drill-casings slidably mounted thereon, the drill-casings being provided with drill-spindles having adjustable drill-bits at the free ends thereof, a rock-shaft disposed through the drill-casings, the outer ends of said rock-shaft being provided with crank-arms, a second rock-shaft disposed through the free ends of the crank-arms of the first rock-shaft so as to oscillate therewith, the outer ends of the second rock-shaft being provided with crank-arms, one of which terminates in an operating lever, means intermediate of the crank-arms of the first rock-shaft and the crank-arms of the second rock-shaft whereby the degree of movement of the crank-arms of the second rock-shaft may be regulated and the length of drill stroke controlled, feed-hooks pivotally secured to the free ends of the crank-arms of the second rock-shaft, the pivotal relation of the feed-hooks, axis of the first rock-shaft and the point of engagement with the rails of the feed-hooks being so correlated that a straight drill thrust will be provided, push-rods pivotally secured to the crank-arms of the first rock-shaft and adapt-

ed to move in the opposite direction of the drill-bits through the movement of the crank-arms of the first rock-shaft, and means having operative relation with the first rock-shaft whereby the drill-casings may be forced toward the rail and the rock-shafts and crank-arms actuated.

27. In a device of the class described, a drill-frame, drill-casings slidably mounted on said frame, the drill-casings being provided with drill-spindles having adjustable drill-bits, adjustable feed-hooks having operative relation with the drill-casings, lubricant and cooling medium mechanism comprising conduits terminating in proximity to the drill-bits, said conduits being slidably mounted on the drill-casings and provided with fluid-controlling valves, push-rods carried by said casings, and means intermediate of said valves and the push-rods whereby the valves will be in open position when the push-rods are in one position and the feed-hooks are in clamping position and discharge of the fluid discontinued when the push-rods are in a second position and the feed-hooks are moved out of clamping position.

28. A device of the class described, comprising a drill-frame, drill-casings slidably mounted on said frame, the drill-casings being provided with drill-spindles having adjustable drill-bits, adjustable feed-hooks operatively connected with the drill-casings, lubricating and cooling medium mechanism comprising conduits terminating in proximity to the drill-bits, said conduits being slidably mounted on the drill-casings and provided with fluid-controlling valves, push-rods adapted to engage with the rails when the drill-bits are being withdrawn, said push-rods being adjustable intermediate of their ends, means intermediate of the push-rods and the valves, and forward of the adjustable point of said push-rods whereby the valves will be in open position when the push-rods are in one position and the valves will be closed when the push-rods are in a second position.
